UNITED STATES PATENT OFFICE.

DAN COYLE, OF CLARKSVILLE, TEXAS.

ROD FOR END-GATES.

SPECIFICATION forming part of Letters Patent No. 437,642, dated September 30, 1890.

Application filed July 10, 1890. Serial No. 358,261. (No model.)

To all whom it may concern:

Be it known that I, DAN COYLE, a citizen of the United States, residing at Clarksville, in the county of Red River and State of Texas, 5 have invented certain new and useful Improvements in Rods for the End-Gates of Wagons or Vehicles of any Kind; and I do hereby declare the following to be a full, clear, and exact description of the invention, such 10 as will enable others skilled in the art to which it appertains to make and use the same.

My invention relates to improvements in rods for the end-gates of wagons or vehicles of any kind; and the object of my improvement is, first, to provide a rod that can be 15 readily attached or detached to the end-gate of any wagon or vehicle; second, to provide a rod that will effectually and rigidly hold the end-gate in position and afford practical 20 facility whereby the end-gates of vehicles can be quickly opened or closed and detached from the wagon-bed or placed in their normal position therein. I attain said object by a novel construction and arrangement of 25 parts, fully described in this specification, and illustrated in the accompanying drawings, in which—

Figure 1 is a view of the rod in the vehicle-gate. Fig. 2 is a similar view slightly modified. Figs. 3 and 4 are detailed views of the 30 rod and its fixtures.

Referring to the drawings, the letter A designates the rod, which is constructed with the centrally-located U-shaped handle a for the 35 purpose of operating the rod and conveniently handling the end-gate of the vehicle when detached from the vehicle-bed, or in attaching and detaching the same to or from the vehicle-bed. This handle is made of elastic steel or any flexible substance that will 40 permit of the rod A being lengthened or shortened by means of screwing or unscrewing the centrally-located section a³. It will be observed that said section contains upon each 45 end the threaded portions a⁵, which are adapted to the corresponding threaded orifices in the rod at the top of the U-shaped handle a, and that there is in this section an orifice a⁶, into which a lever may be placed, whereby 50 the same is screwed or unscrewed. Upon each end of the rod A there are the bent bi-

furcated prongs a', which are vertically adjustable to the reduced portion b of the bolt or end attachments B. Said bolt or end attachment B is secured to the wagon-bed at a 55 point so that it will receive and hold the curved or bent prongs upon the ends of the rod A. It is apparent that when the bent prongs a' are adjusted to the reduced portion b of the bolt B and then turned in an opposite direction it is impossible to extricate the rod until it is again turned in the position in which the prongs were adjusted. This is one of the novel features of my invention and provides a safe and novel manner 60 of locking and unlocking the end-gates of vehicles. I also attach importance to the simplicity of the construction and arrangement of the central removable section a³, whereby the rod A may be readily lengthened or shortened. 65

Fig. 2 is a modified form of my invention without the removable central section a³, and it is especially adapted to the end-gates of vehicles which let down or open and shut. The 70 novel features of this modification consist in the bent bifurcated prongs a' upon each end of the rod, in combination with the end attachments B, whereby the gate is securely and easily locked and unlocked by means of 75 the handle a'.

The dotted lines in Fig. 2 indicate the position the handle a assumes when it is desired to let down the end-gate. When it is desired to detach the end-gate, the handle a is turned 80 to a point directly opposite the position shown in Figs. 1 and 3.

Having fully described my invention and pointed out the novel, practical, and useful features, I deem it useless to further enlarge 85 upon its merits.

What I claim is—

1. A rod for the end-gates of vehicles, provided upon each end with the curved or bent prongs a', the centrally-located U-shaped handle, the central section a³, having upon each end the threaded portions a⁵, which work in corresponding threaded orifices in the rod at the top of the central U-shaped handle, in combination with the bolt B, substantially as 95 described, and for the purpose set forth.

2. A rod for the end-gates of vehicles, hav-

ing the centrally-located handle *a* and the bent bifurcated prongs *a'* upon each end thereof, in combination with the end attachments *B*, adapted to be adjusted between the 5 bifurcated openings, whereby a suitable locking and unlocking mechanism is provided, substantially as described.

In testimony whereof I affix my signature in presence of two witnesses.

DAN COYLE.
